UNITED STATES PATENT OFFICE

114,865

DESIGN FOR A TRAFFIC SIGNAL FACING

Gordon Muir, Grosse Pointe Park, Mich.

Application February 24, 1939, Serial No. 83,190

Term of patent 14 years

To all whom it may concern:

Be it known that I, Gordon Muir, a citizen of the United States, residing at Grosse Pointe Park, county of Wayne, in the State of Michigan, have invented a new, original, and ornamental Design for a Traffic Signal Facing, of which the following is a specification, reference being made to the accompanying drawing, forming part thereof.

The figure is a front elevational view of the traffic signal facing, showing my new design.

The design is substantially flat in cross section.

The characteristic feature of my design resides in the plurality of signal elements arranged as shown, each of said elements being divided into a plurality of figures, said figures being lined for color as shown in the drawing.

I claim:

The ornamental design for a traffic signal facing, as shown and described.

GORDON MUIR.
